TRAFFIC SIGNALING DEVICE

Henry Paul, Philadelphia, Pa.

Application November 13, 1935, Serial No. 49,445

5 Claims. (Cl. 116—63)

The present invention relates to traffic signals and particularly to that type of traffic signal designed to be positioned at an intersection of two or more streets for the purpose of controlling or regulating the flow of traffic at the intersection.

A primary object of the invention is to provide a device of the foregoing type of simpler and more compact construction than the conventional traffic signal now in general use.

10 Another object is to provide a traffic signal which is more adaptable to the varying conditions obtained at street intersections than are prior art devices.

15 A further object is to provide a traffic signal which does not require the use of the conventional bank of three colored lights directed along each of the intersecting streets.

20 Still another object is to provide a traffic signal which does not require the complicated operating and timing mechanisms generally considered necessary in prior devices.

25 In its barest essentials and simplest aspect, the device of the invention consists of three elements: a source of light directed toward a line of traffic to be controlled or regulated; a movable screen interposed between the light source and the line of traffic and being divided into a number of differently colored transparent areas; and means for moving the screen so as to bring each of the 30 colored areas in succession between the light source and the line of traffic, thus producing a series of consecutive colored signals visible to the line of traffic. An essential feature of the invention consists in moving the screen at a constant rate of speed, whereby the duration of the color signals will be proportional to the colored areas, and proportioning the colored areas so as to produce signals of desired relative duration.

35 The inventive idea or concept involved is capable of being embodied in various mechanical forms, several of which will be described in detail for the purpose of illustrating the invention.

40 Figure 1 is a view, partly in vertical section on line 1—1 of Figure 2, of one illustrative embodiment of the invention;

45 Figure 2 is a section taken substantially on line 2—2 of Figure 1;

50 Figure 3 is a section taken substantially on line 3—3 of Figure 1; a portion being broken away for greater clearness;

55 Figure 4 is a face view of a pair of color disks corresponding to one of several streets at an intersection at which the signaling device is to be used;

55 Figure 5 is a similar view of a pair of color disks

corresponding to another of the streets at the intersection;

5 Figure 6 is a horizontal somewhat diagrammatic cross-section through another illustrative embodiment of the invention;

10 Figure 7 is an exploded or developed view of one of the color cylinders constituting an essential element of the device of Figure 6, the cylinder itself and the light source being shown in dotted lines;

15 Figure 8 is a horizontal cross-section through another form of device falling within the purview of my inventive concept;

20 Figure 9 is an exploded or developed view of one of the color cylinders which constitutes an essential part of the device of Figure 8, the cylinder itself and the light source being shown in dotted lines;

25 Figure 10 is a vertical section through still another illustrative embodiment of the invention, the section being taken substantially on line 10—10 of Figure 11;

30 Figure 11 is a horizontal cross-section substantially on line 11—11 of Figure 10;

35 Figure 12 is a flattened-out view of the color cylinder forming an essential constituent element of the device of Figures 10 and 11;

40 Figure 13 is a horizontal cross-section through the color cylinder, substantially on line 13—13 of Figure 12; and

45 Figure 14 is a similar cross-section on line 14—14 of Figure 12.

Referring now to the drawings in greater detail and more particularly to Figures 1, 2 and 3 thereof, it will be noted that the constituent elements 35 of the device are housed within a compact casing indicated by the reference numeral 1. The casing is shown as being supported on a base or pedestal 2 which may be of suitable or desired form or construction, but it is obvious that the casing 40 may be suspended from above in any suitable manner, as for instance in the manner illustrated in Figure 10. The casing is shown surmounted by an ornamental cap 3 which may take a conventional form.

45 The shape of the casing depends to some extent on the number of streets at the intersection. In the case of two streets, the housing may advantageously be of rectangular shape with the four lateral faces facing the intersecting streets. 50 To take care of three intersecting streets, the casing would preferably be hexagonal. A variation would be to make the casing or housing 1 substantially cylindrical in shape with twice as many flattened faces as there are streets at the inter- 55

section. In any event each of the lateral faces is provided with an opening in which may be mounted a cover glass or roundel 4. A hood or visor 5 may be provided for each opening as is usual in the art.

Disposed within the housing 1 is an inner casing 6 which serves to contain the source of light 7. The inner casing may be mounted in any suitable manner as by being suspended from the 10 roof of the outer casing, sufficient space being provided between the two casings for mounting the mechanical elements hereinafter to be described. The inner housing is preferably of the same configuration as the outer casing, and is 15 provided with a series of openings or apertures 8. The number of these openings corresponds to the number of the apertures in the outer casing 1, the two sets of openings being in substantial registration or alignment. The source of light 7 20 may advantageously consist of a single incandescent light for each pair of registering openings. Disposed between each pair of openings is a lens 9 which serves to direct the rays of light originating at 7 through the outer aperture. As 25 shown each lens 9 may be mounted in a plate 10 provided with a suitable opening in alignment with the apertures in the inner and outer casings. The plates 10 may be supported at the proper distance between the two casings 1 and 6 30 in any suitable manner.

Rotatably mounted between each of the lateral walls of the inner casing 6 and the corresponding supporting plate 10 is a color disk, the structure of which will be hereinafter described. In 35 the case of a two-way intersection as in the illustrative embodiment of the invention now being described, there are two pairs of disks designated as 11, 11a and 12, 12a respectively. The first pair of disks corresponds to the North-South street 40 and the second pair corresponds to the East-West street. In the case of a three-way intersection there would, of course, be three pairs of color disks. If one of the intersecting streets should have a blind end at the intersection, the corresponding color disk would be omitted.

Each of the disks may be advantageously mounted on a stub shaft, the ends of which may be supported in any suitable manner, as by means of one of the lateral walls of the inner 50 casing 6 and the corresponding supporting plate 10. The disks may be rotated in any suitable manner. I prefer to drive them from their outer peripheries and to this end I provide each of them with a continuous series of circumferential 55 gear teeth 13 (see Figures 4 and 5). All of the disks are driven by a central horizontally disposed bevel gear 14 through a train of intermediate gears. For this purpose I have provided a series of horizontally disposed shafts 15, equal 60 in number to the color disks. One end of each shaft is journaled in the corresponding supporting plate 10 and the other end is provided with a vertically disposed bevel gear 16 meshing with the central gear 14. Additional supporting 65 means in the form of angle bars 17 may be provided for each shaft. A second gear 18 is mounted on each shaft in position to mesh with the gear teeth 13 on the periphery of the corresponding color disk. The central gear itself is driven 70 by a motor M through the worm gear 19 and the gear wheel 20. The intermediate gearing between the central gear and the color disk are so proportioned that all the disks will be rotated in synchronism at a desired speed. There are two 75 fairly simple ways of changing the speed of the

color disks. One is to change the speed of the motor and the other is to change the gear ratio between the gear teeth 13 and the gear wheel 18.

The electrical connections and circuits for the electric lights and the motor have been omitted as their construction and design form no part of the present invention. Obviously a spring or other type motor may be used.

It has already been stated that the color disks are each provided with a geared periphery 13 to 1 provide means for driving the disks. The central portion 21 of each disk is of opaque material, and the intermediate annular portion 22 thereof is of a transparent material and is divided into a number of colored segments corresponding to the 1 desired signals. In the disks of Figures 4 and 5 the annular area is divided into a red (R), a green (G) and two amber (Y) areas corresponding to a red, a green and two amber signals. Referring first to the North disk of Figure 4; that 2 is the disk facing north, it will be noted that the green area is about 2.5 times the size of the red area, and the red area is about 4 times the size of each of the amber areas which are equal. Since the intermediate portion 21 is annular the 2 segments represented by each of the colors are proportional to their arcuate lengths. In the case of a 40 second cycle, the green on the North disk corresponds to 25 seconds, the red to 10 seconds, and each amber area to 2.5 seconds. 3 Each of the colored areas is adapted to be brought into alignment or registration with the aperture 8 in the inner casing. Hence, as the North disk rotates at a constant speed the green signal is seen for 25 seconds, then an amber signal goes on for 2.5 seconds, then the red for 10 seconds and finally the second amber is seen for 2.5 seconds, after which the cycle is repeated. Referring now to the South disk, it will be noted that the colored areas correspond in color and 4 position to those on the North disk. In other words, the two disks can be superposed. Hence, as the two disks rotate constantly at the same speed, the same signals will be seen on both the North and South sides of the traffic signaling 4 device during the same intervals of time.

Referring now to the East disk (see Figure 5), it will be noted that the area corresponding to the green area of the North or South disk is red in color and that the area corresponding to the red area is green. Also, that the two amber areas of the East disk correspond in position and arcuate length to the same colored areas in the North or South disk. It will also be noted that the East and West disks can be superposed. Hence, in each of these disks, the red area represents 25 seconds of the 40 second cycle, the green area represents 10 seconds and each of the amber areas represents 2.5 seconds as in the North and South disks. Hence, as all four disks rotate 61 at a constant equal speed, the East and West sides of the traffic device will show red while the North and South show green and vice versa. Also, all sides will display amber at the same time.

From what has been said it is thought to be clear that the duration of the different signals can be varied to suit conditions at any particular intersection by varying the arcuate lengths and hence the various segmental areas in the 70 intermediate annular portion 22 of the disks. If it is merely desired to speed or slow up all the signals proportionately, it is only necessary to change the speed of the operating means correspondingly. It is also thought to be clear that 71

instead of housing all the four disks in one casting as in the illustrative embodiment, one or two of the disks may be placed in a separate casting and positioned at a corner of the intersection. 5 In such case the traffic devices should be positioned at least two and possibly at the four corners. Preferably a single driving means would be used for each disk, all the driving means operating in synchronism.

10 Reference will now be had to Figures 6 and 7 which illustrate a second form of the invention. The principal difference between the two embodiments resides in the structure of the color screen. Instead of being in the form of a flat disk as in 15 the first form, the color screen is a tube or cylinder disposed vertically and having a transparent, colored, circumferential band about its mid-section. Referring now to Figure 6, it will be seen that the casing or housing for the mechanical 20 elements is designated by 40 and that it is provided on each of its vertical faces with an aperture 41 to receive a roundel or cover glass (not shown). The color screens which, as has been 25 stated, are tubular or cylindrical in form, are each designated as 42 and serve to house or encase a source of light 43 which is shown to have the form of an incandescent bulb. One of the color screens is illustrated in Figure 7, in which figure the central color band is designated as 44. Inter- 30 posed between each of the color screens (there are as many color screens as apertures 41) and the corresponding wall of the casing 40 is a plate 45 having an aperture 46 in alignment with the aperture 41. The aperture 46 is intended to receive a lens (not shown) for directing the light 35 of the bulb 43 through the outer roundel. The position of the color band 44 on the tube or cylinder 42 is such that it serves to color the light passing from the source of light 43 through the 40 apertures 46 and 41 of the device.

As shown in Figure 7 the color band is divided into a number of differently colored vertical areas or zones designated by the letters Y, R, Y, G to indicate their colors. The arrangement and 45 relative proportions of the areas may be varied to suit individual requirements as in the case of the first embodiment, it being understood that the opposite color screens have the same arrangement and relative proportioning of the color 50 zones, and that in the East and West screens the red zone has the same area and position as the green zone in the North and South screens, and vice versa.

The color tubes or cylinders may be rotated 55 in any desired manner. In Figure 6 they are shown as being operated from a motor M' through intermediate gearing, which consists of a gear 47 for each color screen and secured thereto in any suitable manner, a central gear 48 meshing with all the gears 47, a large worm gear 49 on the same axis as the central gear 48 and a worm 50 on the motor shaft and meshing with the worm gear.

The third embodiment of the invention (see 65 Figures 8 and 9) differs from the one just described in that the color tube or cylinder is disposed horizontally instead of vertically. Referring to Figure 8, the casing for the mechanical elements is designated as 60, the four apertures which face the lines of traffic as 61 and the cylindrical color screens are each denoted by 62. Each cylinder houses a source of light 63 and has a central circumferential band 64 divided into 70 differently colored transparent zones G, Y, R, Y. The structure of the cylinder and the arrange- 75

ment of the zones are exactly the same as in the case of the color screen forming part of the device shown in Figures 6 and 7. However, the cylinders or tubes 62 are disposed horizontally instead of vertically. A lens may be supported by 5 means of a plate 65 between each color cylinder and each aperture 61 to direct the light from the cylinder through said aperture. The numeral 66 designates an aperture in the plate 65 to receive the lens (not shown). 10

Each color cylinder may be driven from a motor M' through a train of intermediate gearing. The gearing may consist of a worm 67 on the motor shaft meshing with a large central worm gear 68, a small central gear 69 on the same shaft as the gear 68, a number of horizontally disposed shafts 70 equal in number to the color cylinders, each having a gear 71 meshing with the small central gear and sprocket connections between the shafts 70 and the corresponding color cylinders. These connections may each consist of a sprocket wheel formed integral with the shaft 70, a sprocket chain 73 and a sprocket wheel 74 secured to the color cylinder, the sprocket chain being trained over both sprocket wheels. 20 25

Referring now to the last illustrative form of the invention (Figures 10 to 14 inclusive) it will be noted that this embodiment has a single vertically disposed cylindrical color screen for all sides of the traffic signal. The casing for the 30 device is indicated by the numeral 80 and is shown as being suspended from an overhead support 81. Obviously, the device may be supported on a base or pedestal, if so desired. Each vertical side of the device which faces toward a line of traffic 35 is provided with an aperture fitted with a roundel or cover glass. The North and South roundels are indicated as 82 and 82a respectively, while the East and West roundels are designated as 83 and 83a respectively. Behind each roundel 40 is positioned a lens. The North and South lenses are denoted by 84 and the East and West lenses are indicated by 85. Each lens may be supported in a suitably mounted plate 86. Hoods or visors 86a may be provided as in the case of the other 45 embodiments of the invention.

The color cylinder is designated by the reference numeral 87 and is shown as being supported upon a turntable 87a which is mounted for rotation on a vertical shaft 88. This shaft and hence 50 the color cylinder is operated by means of a motor M' through the worm 89 and the meshing worm gear 90, the worm 89 being secured to the motor shaft, and the worm gear 90 being fixed to the shaft 88. Suitable bearings may be provided for the rotating parts, both in this embodiment as well as in those previously described.

The color cylinder 87 is provided with one or more circumferential color areas or bands. I prefer to employ as many color bands as there 60 are streets at the intersection, two, in the case of the illustrative embodiment of the invention. The two bands are designated as 91 and 92 respectively, each band being divided into a number of colored transparent zones. The upper 65 band 91 is to serve to color the light passing through the North and South roundels 82 and 82a, and the lower band is to serve to color the light passing through the East and West roundels 83 and 83a. Hence, the North and South roundels and the corresponding lenses 84 are disposed on a level with the upper band while the East and West roundels and lenses 85 are disposed on a level with the lower band. In the 70 case of intersections of three streets, I prefer to 75

use three color bands and hence the roundels facing each street would be on the level of the corresponding color band.

The source of light may be a single incandescent bulb of sufficient power to illuminate both color bands. As shown, I prefer to employ a number of lights, one for each vertical face of the device. The North and South lights are designated as 83 and 84 respectively, while those illuminating the East and West lenses are denoted as 85 and 86. It is to be noted that the lights 83 and 84 are on the level of the upper color band, while the lights 85 and 86 are on the level of the lower band 82. Other possible arrangements of the illuminating means are within the purview of my invention.

Since in the illustrative embodiment each color band is to serve for two opposite faces of the device and the opposite faces must of necessity display the same colored signal during the same interval of time, each band has to represent two cycles and is therefore divided into eight color zones. Two of the zones are red (R), two are green (G) and the remaining four are amber (A) in color. In both bands similarly colored zones are disposed diametrically opposite each other, the amber zones being interposed between the red and green zones so that the signal in changing from red to green or vice versa always passes through amber which serves as a caution signal. The relative proportions of the zones on the bands may be made or varied to suit individual conditions at a given crossing, it being essential that the oppositely disposed zones on each band be the same in color and in area, and that the red and green zones on one band be equal to the green and red zones respectively of the other band. In the illustrative embodiment, the proportions are such as to produce the same signals as in the first three embodiments; that is, assuming a forty second cycle, the green on the upper band and the red on the lower band correspond to 25 seconds, the red on the upper band and the green on the lower band correspond to 10 seconds and all the amber zones correspond to 2.5 seconds each.

The relative arrangement of the two color bands depends upon the angle between the intersecting streets which, of course, is the same as the angle between the adjacent roundels. In the case of two streets intersecting at right angles as in the illustrative embodiment, the red and green zones of one band are disposed at right angles to the contrasting colored zones of the other band. (See Figures 13 and 14.) If the angle between the two streets be less or more than 90° then the angle between the contrasting colors on the two bands will be correspondingly decreased or increased as the case may be. In other words, since the signals at the two intersecting streets are always in opposite phase, it is necessary that the angle between the zones representing the opposite phases on the bands themselves be equal to the angle between the streets. This is thought to be clearly brought out by Figure 12 of the drawings, wherein the cylinder is shown flattened out and the relative positions of the roundels are shown in dotted lines. What has been said applies to intersections of three or more streets, in which case three or more color bands may be used, each representing two cycles and the angles between the zones of contrasting color being equal to the angles between the streets at the intersection.

Under some circumstances it may be desirable

to provide the color cylinder 87 with a single band for all of the streets, in which case all the roundels and their associated lenses would be on the same level. Under other circumstances it may be desirable to have as many color bands as there are roundels, in which case each roundel would have to be on a different level. In this modification each band would not have to represent more than a single cycle; i. e. one succession of red and green zones, with or without one or two amber areas to serve as caution signals.

From the foregoing description of the fourth embodiment it is thought to be clear that at any particular moment each roundel displays the color of the particular zone which happens to be positioned between it and the light source, and that as the cylinder 87 rotates at a constant speed the color at each roundel changes at intervals depending upon the relative proportions of the color zones. It is also thought to be clear that all sides of the device display the amber signal at the same time and that when the North and South signals are red those at the East and West roundels are green and vice versa. If it is desired to change all the time intervals proportionately, it is merely necessary to speed up or slow down the motor and hence the color cylinder correspondingly. The color cylinder is readily removable and may be replaced by one in which the relative widths of the color zones are such as to produce any desired variation in the duration of the signals.

The foregoing specification and description include the essential and distinctive thought of my invention, but it is to be distinctly understood that the same may be modified in various ways and/or combined with various other details without departing from the spirit and scope of the appended claims, in which I intend to claim all the patentable novelty inherent in my invention.

I claim:

1. A traffic signal consisting of a casing provided with a number of pairs of opposite vertical sides, each side provided with an aperture and adapted to be directed toward a line of traffic to be controlled or regulated, a source of light disposed within said casing; a cylinder rotatably mounted within said casing and housing said source of light, said cylinder being provided with spaced circumferential bands, equal in number to the pairs of opposite vertical sides, each band being divided into a number of differently colored zones, each pair of opposite apertures being disposed at the level of one of said bands, and means to rotate said cylinder.

2. The traffic device defined in claim 1, the relative proportions of said zones being equal to the desired relative duration of the signals produced by the device.

3. As an element of a traffic signal, a color screen in the form of a cylinder, said cylinder being provided with two spaced circumferential transparent bands, each of said bands being divided into red and green zones of unequal widths, the red zone on one band being equal in width to the green zone on the other band and vice versa.

4. As an element of a traffic signal, a color screen in the form of a cylinder, said cylinder being provided with two spaced circumferential transparent bands, each of said bands being divided into a red, a green and two amber zones, all the amber zones being equal in width and the

red zone on one band being equal in width to the green zone on the other band and vice versa.

5. As an element of a traffic signal, a color screen in the form of a cylinder, said cylinder being provided with two spaced circumferential transparent bands, each of said bands being divided into a red, a green and two amber zones, all the amber zones being equal in width and the

red zone on one band being equal in width to the green zone on the other band and vice versa, the red and green areas of one band being disposed at an angle to the contrasting colors of the other, said angle being equal to the angle between the 5 two streets at the intersection.

HENRY PAUL.
